UNITED STATES PATENT OFFICE

2,613,024

COLLAPSIBLE CELLULAR CARTON

Kenneth T. Butterly, Kalamazoo, Mich., assignor to Sutherland Paper Company, Kalamazoo, Mich., a corporation of Michigan

Original application November 1, 1945, Serial No. 626,069. Divided and this application January 22, 1947, Serial No. 723,614

2 Claims. (Cl. 229—28)

1

The invention relates to collapsible cellular cartons.

This application is a division of application Serial No. 626,069, filed November 1, 1945, now Patent No. 2,562,233.

The main objects of the invention are:

First, to provide a cellular carton of the egg carton type which is very rigid when set up.

Second, to provide a cellular carton in which the cover is easily engaged in closing the carton, is very securely retained and at the same time may be easily disengaged by manual manipulation.

Objects relating to details and economies of the invention will appear from the description to follow. The invention is defined in the claims.

A preferred embodiment of the invention is illustrated in the accompanying drawings, in which:

Fig. 1 is a perspective view of a carton embodying my invention disclosed.

Fig. 2 is a transverse section on line 2—2 of Fig. 1, eggs being indicated in the transversely aligned cells by dotted lines.

Fig. 3 is an enlarged fragmentary longitudinal section on line 3—3 of Fig. 2.

Fig. 4 is a fragmentary end perspective view showing the cover closure flap partially engaged or disengaged, illustrating the relation of one of the closure flap tongues to one of the combined transverse partition hinge members and keepers.

Fig. 5 is a fragmentary perspective view illustrating further details of the structure.

Fig. 6 is a plan view of the blank from which the carton is formed.

I have illustrated and described my invention as embodied in an egg carton adapted to receive a dozen eggs. The carton is preferably formed of an integral blank as shown in Fig. 6 and comprises front wall 1, rear wall 2, these walls constituting the side walls of the carton.

The bottom members 3 are hingedly secured to the bottom edges of the front and rear walls at 4 preferably by scoring. The bottom members are hingedly joined to the longitudinal partition members 5 along the score lines 6. The bottom members have transverse slots 7 and 8 therein, the slots 8 being the end slots. The outer edges of the slots 8 have inwardly projecting tongues 10. The bottom also has cross incisions 11 intermediate the slots to provide cushioning elements.

The longitudinal partition members 5 are secured together in side by side relation, preferably adhesively, and each member is provided with alternating elongated holes 12 and flaps 13, the

flaps being also elongated and hingedly joined at 14 to their respective partition member. The flaps are somewhat smaller than the holes. The flaps and holes are arranged so that the flap of one longitudinal partition member is aligned with the hole of the other when the partition members are secured together, as is shown in Fig. 2. The slot and flap construction above described is not claimed herein but constitutes the subject matter of the above referred to parent application.

The top members designated generally by the numeral 15 are hingedly connected at their inner edges as indicated at 16 to the upper edges of the longitudinal partition members 5 and they are hingedly connected at 17 to the sealing strips 18. These sealing strips are joined in the blank by the fracturing line 19.

The top members 15 are slotted and scored to provide transverse partitions 20 and end members 21 which are adapted to project through the slots 7 and 8 respectively in the bottom 3 when the carton is erected. The end members 21 have holes 22 therein receiving the tongues 10, the tongues preventing the end members being swung out at the ends of the carton and thereby releasing the contents of the end cells. This end wall structure above described constitutes the subject matter of another application which is a division of the above referred to parent application.

The sealing flaps 18 are secured in an upturned relation to the front and rear wall 1 and 2, as shown in Figs. 2 and 4, the upper edge of the sealing flap secured to the front wall 1 being preferably flush with the upper edge of the front wall. This materially increases the rigidity of the front wall particularly at the upper edge thereof. It is also desirable to increase the rigidity of the rear wall although the increased rigidity of the front wall is more important.

The slits of the top members 15 are arranged so that the hinge members 23 are of triangular shape with their edges 24 facing inwardly. These hinge members constitute keepers with which the tongues 25 on the closure flap 26 of the cover 27 may engage. The cover 27 is hingedly connected to the upper edge of the rear wall at 28. It will be noted that the closure tongues 25 are beveled at 29 and preferably have curved heel portions 30 which facilitates their engagement with the hinge members 23 which, as stated, constitute keepers.

The closure member 26 is disposed on the inner side of the reinforced upper edge portion of the front wall and to close the same it is only necessary to press downwardly on the cover adjacent its front edge. The tongues 25 snap into engage-

ment with their coacting keepers 23. The cover may be released by grasping the same with the thumb engaging its front edge portion of the closure and imparting an inward thrust and upward pull thereon.

To facilitate disengagement, the front wall 1 and sealing strip 18 are provided with a thumb hole or notch 31. This enables the easy grasping of the cover and its closure flap. On the upward pull the tongues 25 snap out from under the keepers, their inclined edges facilitating this. The reinforced upper edge of the front wall is the important feature of this disengagement as it prevents the substantial spacing of the front wall under the disengaging stress. I have indicated the engaging and disengaging movement in Figs. 3 and 4.

The top members are also cut to provide upwardly projecting supporting tongues 32 which support the center of the cover and further facilitate the opening as the cover cannot spring inwardly. These cover supporting members coact with the other features in facilitating the engagement and disengagement of the cover closure.

In cartons embodying my invention the carton is strong and durable and is not likely to be broken or distorted in handling.

I have illustrated and described my invention in a very practical embodiment thereof. I have not attempted to illustrate or describe other embodiments or adaptations as it is believed this disclosure will enable those skilled in the art to embody or adapt my invention as may be desired.

Having thus described my invention, what I claim as new and desire to secure by Letters Patent, is:

1. In a cellular carton, spaced walls, one of said walls constituting a front wall, a bottom member hingedly joined to said walls, a top member hingedly connected to said walls and having a sealing flap integral therewith secured to the inner side of the front wall, the outer edge of the sealing flap being closely adjacent the upper edge of the front wall whereby the upper edge of the front wall is stiffened, the top member being slotted and scored to provide a plurality of transverse partitions and to provide hinge members therefor connected to said sealing flap, a hinged cover having a closure flap on its front edge adapted to be disposed on the inner side of the reinforced upper edge portion of the front wall, said closure flap having a plurality of tongues on its edge adapted to engage beneath said hinge members when the cover is closed, the front wall and sealing flap secured thereto having a finger opening adjacent one end thereof in opposed

relation to the corresponding end of the closure-flap to facilitate forcing said closure flap inwardly and disengagement of the tongues thereof from beneath the hinge members, and facilitating opening of said cover after disengagement of said tongues from said hinge members, said front wall and sealing flap secured thereto fixedly retaining the hinge members against displacement while the closure flap is forced inwardly by a finger in said finger receiving opening and while opening the cover.

2. A cellular carton comprising front and rear walls, bottom members hingedly joined to the lower edges of the front and rear walls, longitudinal partition members hingedly joined to the inner edges of the bottom members and secured in side by side relation, top members hingedly joined to the upper edges of the longitudinal partition members and having sealing flaps integral therewith secured to the inner sides of the front and rear walls, the outer edge of the sealing flap secured to the front wall being closely adjacent to the upper edge of the front wall whereby the upper portion of the front wall is stiffened, said top members being slotted and scored to provide a plurality of transverse partitions and triangular hinge connections therefor to said longitudinal partition members and said sealing flaps, the hinge connections for the transverse partitions to the sealing flap secured to the front wall constituting keepers and having inwardly facing inclined edges, and a cover hingedly joined to the upper edge of the rear wall and having a closure flap on its front edge adapted to be disposed on the inner side of the stiffened upper edge portion of the front wall, said closure flap having a plurality of tongues on its edge facing the inclined edges of said hinge members, the tongues having beveled tips facilitating their engagement with the hinge members, and rounded heel portions further facilitating the engagement of the closure.
